UNITED STATES PATENT OFFICE

124,057

DESIGN FOR A PORTABLE POWER DRIVEN TOOL UNIT

George D. Behlen, Chicago, Ill.

Application January 10, 1940, Serial No. 89,381

Term of patent 7 years

To all whom it may concern:

Be it known that I, George D. Behlen, a citizen of the United States, residing at Chicago, in the county of Cook and State of Illinois, have invented a new, original, and ornamental Design for a Portable Power Driven Tool Unit, of which the following is a specification, reference being had to the accompanying drawing, forming a part thereof, in which:

Fig. 1 is a plan view of a portable power driven tool unit showing my new design; and

Fig. 2 is a side elevational view of the same portable power driven tool unit.

The other side not shown, of the tool unit illustrated on the drawing, is substantially like the side shown, except that the upper rear portion directly opposite the switch has the curvature shown in Fig. 1.

I claim:

The ornamental design for a portable power driven tool unit, substantially as shown and described.

GEORGE D. BEHLEN.
